Kenu, Inc.; Stance Compact Tripod; <https://web.archive.org/web/20150202091854/http://www.kenu.com/products/STANCE>; Archived date: Feb. 2, 2015.*Primary Examiner* — Susan Bennett Hattan*Assistant Examiner* — Leanne Was(74) *Attorney, Agent, or Firm* — Troutman Sanders, LLP(57) **CLAIM**

We claim the ornamental design for a tripod for an electronic device, as shown and described.

DESCRIPTION

FIG. 1 is a front elevational view of a tripod for an electronic device;

FIG. 2 is a rear elevational view thereof;

FIG. 3 is a right side elevational view thereof;

FIG. 4 is a left side elevational view thereof;

FIG. 5 is a top plan view thereof; and

FIG. 6 is a bottom plan view thereof;

FIG. 7 is a top plan view of the tripod for an electronic device in a deployed state;

FIG. 8 is a bottom plan view thereof;

FIG. 9 is a rear elevational view thereof;

FIG. 10 is a front elevational view thereof;

FIG. 11 is a right side elevational view thereof;

FIG. 12 is a left side elevational view thereof; and,

FIG. 13 is a perspective view thereof.

The broken lines are for illustrating unclaimed portions of the tripod for an electronic device; the broken lines form no part of the claimed design.
